CLAIM

We claim the ornamental design for a pelvic and spinal support device, as shown and described.

DESCRIPTION

FIG. 1 is a bottom perspective view of a pelvic and spinal support device shown in an assembled configuration.

FIG. 2 is a top perspective view thereof shown in an assembled configuration.

FIG. 3 is a left side perspective view thereof shown in an assembled configuration.

FIG. 4 is a front elevational view thereof shown in an assembled configuration.

FIG. 5 is a rear elevational view thereof shown in an assembled configuration.

FIG. 6 is a top plan view thereof shown in an assembled configuration.

FIG. 7 is a side elevational view thereof shown in an assembled configuration.

FIG. 8 is a rear perspective view thereof shown in an assembled configuration.

FIG. 9 is a rear perspective view thereof shown with the pelvic and back cushions removed for ease of illustration.

FIG. 10 is a front perspective view thereof shown with the pelvic and back cushions removed for ease of illustration.

FIG. 11 is a second front perspective view thereof shown with the pelvic and back cushions removed for ease of illustration.

FIG. 12 is a right side top perspective view thereof shown with the pelvic and back cushions removed for ease of illustration, the front is shown closer together to illustrate flexibility.

FIG. 13 is a right side bottom perspective view thereof shown with the pelvic and back cushions removed for ease of illustration, the front is shown closer together to illustrate flexibility.

FIG. 14 is a front elevational view thereof shown with the pelvic and back cushions removed for ease of illustration.

FIG. 15 is a top plan view thereof shown with the pelvic and back cushions removed for ease of illustration, the front is shown closer together to illustrate flexibility.

FIG. 16 is an enlarged top plan view of a pelvic cushion shown separately for ease of illustration.

FIG. 17 is an enlarged left rear perspective view of a pelvic cushion shown separately for ease of illustration.

FIG. 18 is an enlarged right rear perspective view of a pelvic cushion shown separately for ease of illustration.

FIG. 19 is an enlarged rear elevational view of a pelvic cushion shown separately for ease of illustration.

FIG. 20 is an enlarged front elevational view of a pelvic cushion shown separately for ease of illustration.

FIG. 21 is an enlarged front elevational view of a back cushion shown separately for ease of illustration.

FIG. 22 is an enlarged front perspective view of a back cushion shown separately for ease of illustration.

FIG. 23 is an enlarged top plan view of a back cushion shown separately for ease of illustration.

FIG. 24 is an enlarged right side elevational view of a back cushion shown separately for ease of illustration.

FIG. 25 is an enlarged right bottom perspective view of a back cushion shown separately for ease of illustration.

FIG. 26 is an enlarged left rear perspective view of a back cushion shown separately for ease of illustration.

FIG. 27 is an enlarged rear elevational view of a back cushion shown separately for ease of illustration; and,

FIG. 28 is a further enlarged left side elevational view of a back cushion shown separately for ease of illustration.
